UNITED STATES PATENT OFFICE.

FERNANDO W. MAKINSTER, OF TILLAMOOK, OREGON.

MATCH SCRATCHER.

Application filed April 12, 1921. Serial No. 460,362.

To all whom it may concern:

Be it known that I, FERNANDO W. MAKINSTER, a citizen of the United States, residing at Tillamook, in the county of Tillamook and State of Oregon, have invented new and useful Improvements in Match Scratchers, of which the following is a specification.

This invention relates to a match igniting means, and its primary object is to provide a device equipped with an abraded surface so formed as to assure positive ignition of a match when it contacts with said surface.

Other objects of this invention are to equip a device of the character described with a fastening element so that it may be readily attached to the apparel of the user, and to provide means formed integral with the abraded surface for holding the said surface out of contact with the apparel of the user to thus minimize the danger of an accident during the igniting operation.

A further object of this invention is to provide a device of the character described which is simple in construction, inexpensive in manufacture, positive in action, highly serviceable, and ornamental in appearance.

Other objects and advantages will be apparent during the course of the following description.

In the accompanying drawings forming a part of the specification and in which like numerals are employed to designate like parts throughout the same.

Fig. 1 is a front elevation of my device,
Fig. 2 is a side elevation of the same,

Fig. 3 is a vertical section through the device, taken on the line 3—3 of Fig. 1,

Fig. 4 is a rear elevation of the same, and

Fig. 5 is a horizontal section of the device, taken on the line 5—5 of Fig. 1.

In the accompanying drawing wherein for the purpose of illustration is shown a pre-

ferred embodiment of my invention, the numeral 6 designates a substantially oval plate formed with a peripheral rim 7 and provided with a concave abraded surface, which surface is formed by a plurality of

spaced left and right ribs 8 and 9, respectively. The respective ribs of the left side of the surface extend from a point adjacent the outer rim of the oval plate and terminate centrally of said abraded surface and

converge with the respective corresponding

ribs in turn extending from the outer rim of the right side of the surface.

From this construction it will be apparent that a match to be scratched, when positioned within outer rim of the plate will be directed towards the center of the abraded surface to be there ignited and thus minimize the danger of flying sparks being carried to the apparel of the user.

I furthermore propose to form extensions 65 10 and 11, on the rim to thus hold the abraded surface in a fixed position with relation to the apparel of the user of the device, which extensions serve to increase the protection of the user from the danger of 70 the above mentioned flying sparks.

As shown to advantage in Figs. 2, 3, and 4, a bifurcated extension 12, is provided on the rear of the plate 6, which portion has pivoted thereon at 13, a fastening element 75 or pin 14. The pointed extremity of this pin is adapted to be readily received in a hook element 15, likewise, formed integral with the rear surface of the plate. As will be readily apparent this construction affords 80 a convenient means for fastening the device either to the apparel of the person or to a stationary object.

While I preferably intend the device for use in conjunction with the apparel of the 85 user, still it will be readily apparent that the device can be conveniently placed on objects of various descriptions for convenient use.

It is to be understood that the form of 90 my invention herewith shown and described, is to be taken as a preferred example of the same, and that various changes in the shape, size and arrangement of parts may be resorted to without departing from the spirit 95 of the invention or the scope of the subjoined claim.

Having thus described my invention, I claim:

A match striker adapted to be fastened 100 to a garment and comprising a plate provided with an outer rim and a concave abraded surface consisting of a plurality of ribs extending from the rim of the plate and forming angles at their juncture, substantially as and for the purpose described.

In testimony whereof I, affix my signature.

FERNANDO W. MAKINSTER.
